UNITED STATES PATENT OFFICE.

WALTER P. HINES, OF PORTSMOUTH, VIRGINIA, ASSIGNOR OF ONE-HALF
TO ALBERT N. PALMER, OF NORFOLK, VIRGINIA.

TROLLEY-SWITCH.

SPECIFICATION forming part of Letters Patent No. 681,119, dated August 20, 1901.

Application filed October 20, 1900. Serial No. 33,757. (No model.)

To all whom it may concern:

Be it known that I, WALTER P. HINES, a citizen of the United States, residing at Portsmouth, in the county of Norfolk and State of 5 Virginia, have invented a new and useful Trolley-Switch, of which the following is a specification.

This invention relates to electric-railway equipments in general, and more specifically 10 to the class of overhead-trolley equipments, and it has specific reference to the trolley-wheel and its mounting on the trolley-arm and also to the trolley-switch for directing the trolley-wheel to the proper wire at a turnout. 15 The object of the invention is to provide a simple and efficient trolley wherein the head will be pivotally mounted to swing in a vertical plane transversely of the trolley-wire, so that the trolley-wheel may be held in contact with the wire at such times as when the car may jerk violently from side to side and at which time the common form of wheel is usually displaced from the trolley-wire, an additional object of the invention being to 20 provide for preventing downward displacement of the trolley-wheel from the wire excepting at such times as when the trolley is to be intentionally removed from the trolley-wire. 25

30 A further object of the invention is to provide a specific form of switch for use at a turnout and which will coöperate with the mechanism of the trolley to disengage its retaining means and permit of the trolley-wheel 35 passing to a different member of the switch than that to which the engaged trolley-wire is attached.

Additional objects and advantages of the invention will be evident from the following 40 description.

In the drawings forming a portion of this specification, and in which like numerals of reference indicate similar parts in the several views, Figure 1 is a perspective view showing 45 portions of a main and a branch trolley-wire connected with a turnout-switch and illustrating the form and position of the trolley when approaching the switch on the main line. Fig. 2 is a top plan view of the switch 50 in its open position, as when the trolley is pass-

ing from the branch wire to the main-line wire. Fig. 3 is a vertical section through the trolley-head and showing the positions of the parts as when engaged with the trolley-wire, the retainers being shown in elevation. Fig. 55 4 is a vertical section taken in the plane of the front face of the trolley-head and showing the head and its parts in elevation, the retainers being in their open or disengaging position. Fig. 5 is a perspective view showing the guide with which the lower end of the trolley-head is slidably engaged.

Referring now to the drawings, and more particularly to Figs. 1, 3, and 4 thereof, 10 60 represents the trolley-arm, the lower end of which is provided with the usual mountings, which need not be shown, the upper end of the arm being disposed rearwardly and horizontally, as shown at 11, the rear extremity of this rearwardly-disposed portion being reduced to form a spindle 12. Upon the spindle 12 is disposed the vertical trolley-head 13, which projects both above and below the trolley-arm, as shown at 14 and 15, the upwardly-projecting portion being bifurcated to form 70 75 two arms 16 and 17, and between these two arms is rotatably mounted the trolley-wheel 18 upon a spindle 19 in the usual manner.

To hold the trolley-head yieldably in a vertical position to permit lateral pivotal movement thereof, a passage 20 is formed transversely through its lower end, and in this passage is slidably mounted a guide-bar 21, the ends of the bar projecting beyond the side faces of the trolley-head. Upon the projecting end portions of the guide-bar 21 are fixed leaf-springs 22, which are disposed upwardly and inwardly, their upper ends bearing against the side faces of the lower portion of the trolley-head. These springs hold 80 85 the guide-bar normally with its ends projecting equal distances from the side faces of the head; but they permit of movement of the lower end of the head relatively to the guide-bar when the latter is held stationary. 90

To hold the guide-bar 21 rigid with respect to the trolley-arm, a brace-bar 23 has one end engaged with the trolley-arm, while its rear end is bifurcated to form arms 24' and 25', these arms being connected with the outer 95 100

ends of the guide-bar 21, as shown. This brace-bar maintains the position of the guide-bar relatively to the trolley-arm for the purpose above described. With this feature of the structure it will be seen that the trolley-head while being held normally vertical may have a lateral swinging movement, so that sudden sidewise jerking of the trolley-arm will not jerk the trolley-wheel from the wire.

To further insure against accidental displacement of the trolley-wheel from the trolley-wire, retainers are provided. These retainers comprise each an arm 24, including an upper member 25 and a lower member 26, disposed at an obtuse angle to each other, and each of these arms is pivotally mounted on a side of the trolley-head through the medium of a pivot-pin engaged with the arm at its angle and with ears 27 and 28, lying at opposite sides of the arm. The upper ends of the arms 24 are bent inwardly over the upper ends of the arms 16 and 17 to just cover the interspaces between the side faces of the trolley-wheel and the inner faces of the arms 16 and 17, and on the upper faces of these inwardly-bent portions of the arms 24 are mounted rollers 29 upon spindles 30, said rollers being disposed to rotate in a common plane at right angles to the plane of the rotation of the trolley-wheel and to lie above the trolley-wire when the trolley-wheel is in engagement with the wire, at which time the rollers are in peripheral contact.

To remove the rollers from their positions above the trolley-wire when it is desired to draw the trolley down from the wire, a line 31, having forks 32 and 33 at its upper end, has said forks connected with the outwardly-directed lower ends of the arms 24, whereby when the line is drawn downwardly the lower ends of the arms will be drawn toward each other and at the same time the trolley-arm will be drawn downwardly, the tension of the springs at the base of the trolley being greater than the tension of the springs 34 and 35, which hold the lower ends of the arms 24 spaced apart. The leaf-springs 34 and 35 are secured to the side faces of the lower portion 15 of the trolley-head, the springs being diverged laterally to rest with their lower ends against the inner face of the arms 24, with which they are in slidable contact. In the use of a trolley of this structure when the trolley is in operation and comes in on a branch line to the main line there must be provided some means at the turnout-switch for permitting the trolley to pass to the main wire, and also means must be provided for permitting the trolley when moving down the main wire to pass the branch wire. These features are embodied in the turnout-switch shown in Figs. 1 and 2, in which the branch wire is connected directly with one section of the main wire at one side of the switch through an element of the switch, the section of the main line at the opposite side of the

switch from the first-named main-line section being connected with a different member of the switch. This switch comprises a supporting-plate 40, adapted for connection of a hanger thereto, and at the ends of which plate are depending flanges 41 and 42, which converge in conformity with the convergence of the main-line wire and the branch wire. To the flange 41 is connected a plate 43, while to the flange 42 is connected a plate 44, the plate 43 forming one leaf of a hinge, including a second leaf or plate 45. The plates 43 and 44 converge in conformity with the flanges to which they are attached, the plate 45 being of such length as to project beyond the convergent end of the plate 44, against which latter it is held yieldably by means of a leaf-spring 46, bearing against the plate 45 and having its rear end portion riveted to the plate 43. The plate 45 projects only beyond the end of the body portion of plate 44, which latter has a narrowed extension 47, which lies flat against and projects slightly beyond the plate 45, this extension 47 lying between a cam-plate 48, riveted onto the adjacent face of the plate 45, and the forward end of a flange 49, formed upon or secured to the adjacent face of plate 45 below said extension. The forward or convergent end of the plate 44 has its lower edge slanted upwardly, so that said plate is tapered to the narrow extension 47, and the forward end of plate 45 is likewise tapered, so that the flange 49 leads upwardly to the extension 47. A flange 50 may be formed upon or secured to the lower portion of plate 45 opposite to the flange 49, and flanges 51 and 52 are secured to or formed upon the plate 43 in alignment with flanges 49 and 50. One end of the main-line section 53 is connected directly with the extension 47 of the plate 44 to form a continuation thereof, while the adjacent end of the next main-line section is connected to the farther end of the plate 43 and at the lower edge thereof, the branch wire 54 being connected with the outer end of the plate 44, at the lower edge thereof.

The operation of the switch is as follows: The parts being in the position shown in Fig. 1 of the drawings, when the trolley reaches the switch the cam-plate 48 enters between the retaining-rollers on the trolley-head and moves them, with the arms 24, outwardly to permit the trolley-wheel to move downwardly from the wire, and when this movement of the rollers has taken place the trolley-wheel strikes the forward downwardly-curved edge of the plate 45 and passes therealong and along the lower edge of plate 43 until it passes to the trolley-wire at the rear of the switch. The rollers on the arms 24 run along the side flanges at the lower edges of the plates 41 and 45 and are held spaced apart, and when said rollers move from the rear ends of these flanges the springs 34 and 35 operate the arms 24 to reengage the rollers over the

trolley-wire. In the return movement of the trolley along the main line, if there be such return movement, the rollers will be separated by the rear edge of plate 43, permitting the trolley-wheel to return along the lower edges of plates 43 and 45, and so on to the extension 47 and to the wire attached thereto. A trolley coming in over the branch line to the main line will strike the lower edge of the plate 44, the rollers on arms 24 passing at opposite sides of the plate, the innermost roller entering between plates 44 and 45 at the extension 47 of the latter and by engaging plate 45 will press it laterally to permit the trolley to pass beyond the plate 45. When the trolley has passed from the switch, the retaining-rollers reengage over the wire, which is now the main-line wire.

With this construction it will be seen that the trolley-retainers are automatically shifted from one wire to another, while when in their engaged positions they prevent displacement of the trolley-wheel.

It will be understood that in practice various modifications of the specific construction shown may be made and that any suitable materials and proportions may be used for the various parts without departing from the spirit of the invention.

30. What is claimed is—

1. In a trolley system, the combination with main and branch line trolley-wires, of a trolley comprising a wheel for contact with the wire and retainers held yieldably in their operative positions transversely of the wheel and above the wire, and a turnout-switch connecting the branch wire with the main wire, said switch comprising a plate having a main-line section attached to one end and a branch-line section attached to its opposite end, and a second plate disposed divergently from the first plate, means for holding the plates yieldably in contact at their converging ends, the second plate having a contacting portion leading downwardly from the line-wire which is attached to the first plate, to receive the trolley-wheel and guide it from said line-wire, and the first plate having a cam portion for engagement between the retainers to separate them and permit downward movement of the trolley-wheel from the line-wire.

2. In a trolley system, the combination with a trolley-wheel having retainers disposed to lie normally at the opposite side of a wire to hold the wheel in place thereon and means for holding the retainers yieldably in operative position, of main and branch line wires having a connecting turnout-switch, one member of the switch having a section of the main wire attached at one end and the branch wire attached at its opposite end, and a second member of the switch having a main-line section attached at one end and its opposite end disposed to receive the trolley-wheel

from the first main-line section, and means carried by the switch for engagement with the retainers for moving them to inoperative positions to permit the trolley-wheel to pass from the main-line wire that is attached to the first plate.

3. In a trolley system, a trolley comprising an arm, a head pivoted to the arm for operative movement in a vertical plane transversely of a trolley-wire, and a wheel carried by the head.

4. A trolley comprising an arm, a head pivoted to the arm for operative movement in a vertical plane transversely of a trolley-wire, a wheel carried by the head for engagement with the wire, and means for holding the head yieldably against pivotal movement.

5. A trolley comprising an arm, a head pivoted to the arm for movement in a plane at an angle to the direction of progress of the trolley, said head extending above and below the end of the arm, a wheel mounted in the upper end of the head for contact with a wire, a guide-bar connected with the arm and slidably engaged with the head, and springs sustained by the guide-bar and disposed to hold the head yieldably against pivotal movement.

6. A trolley comprising an arm having a head adapted for lateral tilting movement on the arm, a trolley-wheel rotatably mounted in the head and adapted for bodily tilting movement therewith, retaining-arms pivoted on the side faces of the head and having their upper ends projected inwardly and provided with means for bridging a wire above the trolley-wheel, the lower portions of the arms lying normally divergent, means for holding the arms yieldably in their operative positions, and means for retracting the arms to release the wire.

7. A trolley comprising an arm having a head adapted for lateral tilting movement on the arm, a trolley-wheel mounted in the head and adapted for bodily tilting movement therewith, retaining-arms pivoted at the sides of the head, rollers carried by the arms and adapted to lie in mutual peripheral contact above and transversely of the trolley-wheel, the lower portions of the arms lying divergent, means for holding the arms yieldably with the rollers in operative positions, and means for moving the arms against said holding means.

8. A trolley comprising an arm having an upper rearwardly-directed end provided with a spindle, a head pivotally mounted upon the spindle for movement at an angle to the direction of progress of the trolley, said head extending above and below the rearwardly-directed portion of the arm and having its upper portion bifurcated, a trolley-wheel disposed between the bifurcations of the head, retainers mounted upon the head for movement into and out of position above and

transversely of the wheel, a guide-bar slida-
bly engaged with the lower end of the head,
springs disposed between the bar and head
to hold the latter yieldably in a predeter-
5 mined relation to the bar, and means con-
nected with the bar and trolley-arm for hold-
ing the bar in fixed relation to the arm.

In testimony that I claim the foregoing as
my own I have hereto affixed my signature in
the presence of two witnesses.

WALTER P. HINES.
